UNITED STATES PATENT OFFICE.

LAWRENCE MARION GARMAN, OF EL RENO, OKLAHOMA.

SIGNAL-BELL FOR BOWLING-ALLEYS.

1,146,492.

Specification of Letters Patent. Patented July 13, 1915.

Application filed February 24, 1914. Serial No. 820,786.

To all whom it may concern:

Be it known that I, LAWRENCE MARION GARMAN, a citizen of the United States, residing at El Reno, Oklahoma, in the county of Canadian and State of Oklahoma, have invented a new and useful Signal-Bell for Bowling-Alleys, of which the following is a specification.

This invention relates to new and useful improvements in signal bells for bowling alleys and the object in view is to produce a device of this nature so arranged that, when the last of a series of ten pins is knocked down by the rolling of a ball, a signal may be sounded.

My invention comprises various details of construction, combinations and arrangements of parts which will be hereinafter fully described, shown in the accompanying drawings and then specifically defined in the appended claims.

I illustrate my invention in the accompanying drawings, in which:

Figure 1 is a view in elevation of pins set up, parts of the frame being in section. Fig. 2 is a side elevation of the pins, the casing being shown in section. Fig. 3 is a central sectional view showing the spring-pressed means for automatically ringing a bell. Fig. 4 is a detail view of a bell striking hammer. Fig. 5 is a top plan view, and of the various pins and connections therewith. Fig. 6 is an enlarged detail in elevation of one of the pins and connections therewith.

Reference now being had to the details of the drawings by letter, A designates a standard of the frame A', and B the alley. A series of rods C, shown clearly in Fig. 5 of the drawings, is mounted in a horizontal plane in the opposite walls of the frame and a series of ten pins, each designated by letter D, is pivotally mounted upon said rods, preferably in triangular or pyramidal shape, as shown.

The lower portion of each pin is positioned a slight distance above the alley and so arranged that, when a ball strikes against the lower portion of the pin, it may be caused to tilt toward a horizontal position. Each pin has a lateral projection E adjacent to its pivotal point at right angles to the pin and to which projection a head F of the plunger F' is pivotally connected. A coiled spring I bears yieldingly against said head and a portion of the lateral projection H

upon the standard and tends to hold the pin either in a vertical or substantially horizontal position, accordingly as to whether the spring is positioned as shown in solid lines in Fig. 6 of the drawings and in which position the pivotal point of connection of the head F and plunger F' will be below a line drawn through the hinge of the pin and the abutment H, or in the position shown in dotted lines when tilted.

A reel frame K is fastened to the standard, and L designates a shaft journaled in said frame and to which a reel K' is fixed. A coiled spring K² has one end fixed to the frame K and its other end secured to the shaft L. A bell-striking hammer I is fastened to the shaft L and one end thereof which, when the reel is under tension of said spring K², is positioned a slight distance 75 from the bell N, is adapted to strike the latter each time the shaft is given a partial revolution. Ropes O are secured to and adapted to wind about the reel and each rope is secured to a bail-shaped member O', shown clearly in Fig. 3 of the drawings, each member having angled ends O² which are pivotally connected to eyes R fastened to pins adjacent to and below their pivotal points.

When the pins are set up in readiness for use, the various ropes are held taut by the tension of the spring K acting upon the reel and the springs I', it being understood that the tension of any one spring I', when acting to hold a pin in an upright position, is sufficient to prevent the reel from making a partial revolution.

It will be noted that, when a pin is tilted by the rolling of a ball against the lower end, the pin will tilt and the tension of the spring bearing against the pin when tilted will hold the pin in a substantially horizontal position and which will be the case with all of the pins as they are tilted. It will be noted that, when the pin tilts, the rope connected thereto will be slack and, when all the pins but one are tilted, the rope connected to the last pin will be taut and will tend to still hold the reel from rotating under the action of the pin connected therewith but, when the last pin tilts causing the rope connected thereto to slack, the reel will be allowed to make a partial revolution under the tension of its spring to cause the hammer to strike the bell to give a signal.

The various pins may be turned by hand

to their normal positions and be held in such positions by the coiled springs which are mounted upon the various plungers connected thereto.

5. What I claim to be new is:—

1. An automatic apparatus for bowling alleys comprising a frame, a series of pivotally mounted ten pins thereon, a spring-pressed reel, ropes fastened one to each pin and winding about said reel, spring-pressed means connected to each pin and adapted to hold the pins either in an upright or horizontal position, and means for sounding an alarm when all of the pins are tilted to horizontal positions.

2. An automatic apparatus for bowling alleys comprising a frame, a series of pivotally mounted ten pins thereon, a spring-pressed reel, ropes fastened one to each pin and winding about said reel, spring-pressed means connected to each pin and adapted to hold the pins either in an upright or horizontal positions.

20 3. An automatic apparatus for bowling alleys comprising a frame, a series of pivotally mounted ten pins thereon, a lateral projection upon each pin, a spring-pressed plunger having a head pivotally connected to said projection and designed to hold the pin in vertical or horizontal positions, a spring-pressed reel, ropes secured to and winding thereon, and a bail-shaped member secured to each rope and having its ends pivotally connected to a pin, and an alarm adapted to be actuated by rotation of the reel when all the pins are tilted.

zontal position, a bell and a striker rotating with the reel, said reel adapted to rotate only when all of the pins are tilted to horizontal position. 25

3. An automatic apparatus for bowling alleys comprising a frame, a series of pivotally mounted ten pins thereon, a lateral projection upon each pin, a spring-pressed 30 plunger having a head pivotally connected to said projection and designed to hold the pin in vertical or horizontal positions, a spring-pressed reel, ropes secured to and winding thereon, and a bail-shaped member secured to each rope and having its ends 35 pivotally connected to a pin, and an alarm adapted to be actuated by rotation of the reel when all the pins are tilted.

LAWRENCE MARION GARMAN.
